UNITED STATES PATENT OFFICE.

WILLIAM H. MATHEE, OF NEW BRUNSWICK, NEW JERSEY, ASSIGNOR TO JOHNSON & JOHNSON, OF NEW BRUNSWICK, NEW JERSEY, A CORPORATION OF NEW JERSEY.

DESIGN FOR A COUNTER DISPLAY APPLIANCE.

Application filed April 2, 1928. Serial No. 26,103. Term of patent 14 years.

To all whom it may concern:

Be it known that I, WILLIAM H. MATHEE, a citizen of the United States, residing at New Brunswick, in the county of Middlesex and State of New Jersey, have invented a new, original, and ornamental Design for a Counter Display Appliance, of which the following is a specification, reference being

had to the accompanying drawings, forming part thereof.

Figure 1 is a front perspective view.

Fig. 2 is a rear elevational view.

I claim:

The ornamental design for a counter display appliance, as shown.

WILLIAM H. MATHEE.
